UNITED STATES PATENT OFFICE.

ELIZABETH B. McKNIGHT, OF OCEAN VIEW, VIRGINIA.

SHIRT CUFF.

Application filed October 10, 1922. Serial No. 593,535.

To all whom it may concern:

Be it known that I, ELIZABETH B. McKNIGHT, a citizen of the United States, and resident of Ocean View, in the county of Norfolk and State of Virginia, have invented certain new and useful Improvements in Shirt Cuffs, of which the following is a specification, reference being had therein to the accompanying drawing.

10 With shirts having soft non-detachable cuffs, as well as other shirts and cuffs, it is very desirable to have the cuffs clean; yet cuffs quickly and unavoidably show signs of use. For this reason, many expedients 15 are adapted for protecting cuffs or for readjusting them in such a way as to have only clean surfaces visible. Even the most widely known makers of high grade goods have adopted and spent large amounts in 20 advertising such expedients.

The object of this invention is to provide shirts and cuffs, at low cost, such as allow repeated readjustment to expose in succession fresh surfaces, and to do this by simple 25 readily embodied construction, such as lends itself to ready washing, easy flat ironing, use with no linings, quick adjustment requiring no special skill, and pleasing appearance at all times.

30 In the accompanying partly diagrammatic drawings:

Fig. 1 shows one broad face of a cuff blank.

Fig. 2 is an edge view of the same blank.

35 Fig. 3 is an edge view of the same blank partly folded, the folds being separated.

Fig. 4 shows the same blank further folded.

Fig. 5 is an edge view similar to Fig. 3 40 but with folds brought nearer together and sewing indicated.

Fig. 6 is a side view with one flap folded inside the cuff body.

Fig. 7 is another edge view similar to 45 Fig. 3.

Fig. 8 is a side view of the sleeve end and cuff as they appear in use.

In these figures the cuff blank and the complete cuff consist of a single rectangular piece of fabric X as wide as the circumferential length of the cuff and substantially 50 in length equal to six times the width of the cuff, or consisting of equal areas A, B, C, D, E, F. This blank is folded transversely between the areas or sections C and 55 D, and at the opposite sides of the areas

C and D the parts A, B, and E, F, are folded back as shown in Fig. 3, and their terminal ends are sewed directly to an interposed sleeve G, without wristband. None of the 60 portions overlapped by folding are centrally connected, but the lateral margins of A and F are sewed together without overlapping, and the corresponding margins of B and C and of D and E are sewed together in like 65 manner, as suggested in Fig. 5, so that the main body A, F, is provided with distinct flaps M and N.

Obviously these two flaps, which are double, can be folded back in either direction upon the body portion A, F, or can be folded oppositely, as in Fig. 4.

As the folds are not centrally united, either flap M or N, as shown in Fig. 6, can be pushed or folded in the space between 75 A and F and the other flap can be folded over upon the body A, F, or O, Fig. 6. Button-holes pass through all the folds and register so that studs may be inserted in whatever way the parts are folded. Obviously, 80 many fresh surfaces are available. Fig. 8 shows the sleeve and folded cuff. From the description, it will be seen that none of the overlying sections are sewed together except that the sections A, F are stitched to 85 the intermediate sleeve and each pair of sections, AF, BC, DE, has its corresponding end margins sewed together as above set forth, that no linings are used, that no fold has any gathers or plaits, but that all are 90 at all times merely layers of the fabric. The washing is extremely simple and every part is ironed flat and when ironed consists of two layers of the fabric, usually without starch, but not necessarily so.

What I claim is:

1. A cuff consisting of a long strip of fabric approximately equal in width to the length of a cuff, folded on approximately 100 equidistant parallel transverse lines to form sections of the size and shape of a cuff, the first and last, second and third, fourth and fifth sections being brought by the folding into registering contact and each of these pairs of sections having its lateral end margins only sewed together, as and for the 105 purpose set forth.

2. A cuff consisting of a fabric strip, the length of which is approximately a multiple 110 of a cuff's width, folded transversely at its middle, having its end margins sewed to a sleeve and its lateral registering margins

sewed together to a cuff's width from the sleeve, its middle mold carried back, between adjacent portions of the strip, to the line between the terminals of the sewing uniting 5 said lateral margins, thereby forming flaps projecting beyond said line, each flap having its registering lateral margins, only, sewed together.

3. A cuff consisting of a rectangular fabric strip equal in width to the length of a cuff, folded transversely on approximately equally spaced parallel lines at a cuff's width apart, to form an even number of sections approximately equal in width and length to

a cuff, the terminal margins of the strip 15 being sewed to a sleeve and the registering lateral margins being sewed together to a distance from the sleeve equal to a cuff's width, each two succeeding pairs of sections being folded together and having their 20 lateral registering margins, only, sewed together, whereby a plurality of flaps are formed at the outer side of united sections sewed to the sleeve.

In testimony whereof I hereunto affix my 25 signature.

ELIZABETH B. McKNIGHT.
